UNITED STATES PATENT OFFICE.

THOMAS H. BAKER, OF BALTIMORE, MARYLAND.

SLIDING-DOOR FASTENING.

1,331,858.

Specification of Letters Patent.

Patented Feb. 24, 1920.

Application filed June 10, 1919. Serial No. 303,213.

To all whom it may concern:

Be it known that I, THOMAS H. BAKER, a citizen of the United States of America, residing at 2400 Maryland avenue, city of 5 Baltimore, State of Maryland, have invented certain new and useful Improvements in Sliding-Door Fastenings, of which the following is a specification.

The invention will be described with 10 special reference to the sliding doors used on freight or box cars, but is equally applicable to the sliding doors used in warehouses and similar buildings. The usual method of fastening car doors is to provide 15 a lock and a seal, which are applied to the front edge of the door. Such fasteners have the defect that it is comparatively easy in many cases to gain access to the car at the back edge of the door without disturbing the 20 seal. Devices have been proposed which overcome this difficulty to a greater or less extent, but they are complicated and expensive.

The main object is to provide an attachment 25 that will lock the door effectively at the front and the back edges, and which will at the same time be simple to operate and inexpensive.

Another object of the invention is to provide 30 an efficient and simple method of closing the space between the edge of the door and the wall of the structure to make the door fire-proof, and to seal the door against other destructive elements.

The invention further contemplates the 35 attainment of all of the above mentioned objects in a single structure. Other more specific objects will appear in the following descriptions.

The accompanying drawings show a door 40 embodying the various features of the invention.

Figure 1 is an elevation of a sliding door on a box car showing the location of the various parts of the device.

Fig. 2 is a perspective view showing more clearly the operation of the parts of the device which lock the rear edge of the door.

Fig. 3 is a modification of the device 50 shown in Fig. 1, to include a fire-proof feature.

Fig. 4 is a horizontal section on the line A, A in Fig. 3.

In Fig. 1 there is a box car 1, shown fragmentarily, provided with a door 2, having

attached to its upper edge brackets 3, carrying rollers 4, adapted to run on track 5. On the front edge of the door one or more bolts or bars 6 are securely fastened to the door. On the frame of the door one or more sockets 60 7 are securely fastened. When the door 2 is closed by sliding to the left, bolt 6 enters the socket 7 and thereby automatically locks the front edge of the door against up and down motion, or in and out motion. It is also to 65 be noted that the door may be opened without the previous releasing of any device at the front edge of the door.

In Fig. 2 is shown a plate 8 securely attached to the car body adjacent to the back 70 edge of the door when closed. Hinged to plate 8 is a plate 9 which may be swung to a position against the car body so that the door can be freely opened or it may be swung against the edge of the door. When 75 plate 9 is swung against the edge of the door, openings 10 therein receive projections 11 on a plate 12, securely fastened to the back edge of the door. On top of plate 12 is mounted a plate 13 having a groove or 80 seat portion 14, adapted to receive a bolt 15. Bolt 15 has on its outer end a locking arm 16. The bolt is mounted to rotate and in one position of bolt 15, the arm 16 swings over and locks plate 9 against the edge of the 85 door 2 and over the projections 11. The other end of bolt 15 has an actuating arm 17, which projects through an opening 18 in seat 14. The arm 17 of bolt 15 has near its lower end an eye 19 which, in the locked position (the position shown in all the figures), is opposite the eye 20 in the end of a pin 21, fastened to the door 2. Eyes 19 and 20 are adapted to receive the wire of a seal 22 when the device is in the locked position, and thus prevent the opening of the door 2 unless the seal 22 is broken. The end of the actuating 90 arm 17 extends beyond pin 21, and provides a convenient handle to rotate bolt 15 until the arm 17 assumes a position in which locking arm 16 clears plate 9, so that it is free to turn against the body of the car. A slot 23 in seat 14 is provided into which arm 17 95 may be slid for the purpose of clearing plate 9. 100

It will be noted that the bolt 15 passes through a notch 24 in plate 9, and that the arm 17 must be turned almost to the upright position before the door 2 is unlocked. Attention is also called to the fact that plate 110

12 extends slightly beyond the edge of the door 2. When it is desired to open the door the lower end of arm 17 is grasped turned to the upright position, pushed to the right and thus enters the slot 23 and with continued pressure the projection 17 will move the door and turn plate 9 against the car body and allow the door to open, so that the door is opened by a single operation.

10 All parts are fastened by bolts 24 having a square portion fitting into square holes in the parts to be fastened so they cannot be turned from the outside.

15 In the modification shown in Figs. 3 and 4, parts 27, 28, 29 and 30 correspond to parts 13, 15, 21 and 11 in Fig. 2. Attached to the body of the car is a plate 31, which may extend the full length of the car door. Hinged to plate 31 is another plate 32, which

20 also extends the full length of the car door. Plate 32 corresponds to plate 9 and operates along with the parts 27, 28, 29 and 30 in a manner exactly corresponding to the operation of the corresponding parts in Figs. 1 and 2. By having the plate 32 extend the full length of the car door the opening between the car door and the body of the car is completely closed against sparks or other agencies harmful to the contents of the car.

25 Such protection is particularly valuable for cars carrying explosives or other inflammable materials.

There may be attached to the arm 17 an

30 insignia or marker in the form of plate 33 bearing a shield or other designation to show 35 that the car is sealed and protected and afford a deterrent influence to prevent tampering with the car.

What I claim is:

40 1. A fastening for sliding doors, consisting of a hinged member on the door frame at the rear of the door, the hinge pivot being substantially vertical, so that the hinged member swings against the rear edge of the door, the rear edge of the door having projections in the plane of the door, interlocking with the hinged member, and means on the door for locking the hinged member against the edge of the door, in engagement with the said projections.

45 2. In a fastening for sliding doors, a hinged plate on the frame at the rear of the door opening, the pivot of the hinge being vertical, so that the plate swings against the rear edge of the door, the door having means 50 adapted to engage the plate, and a rotary bolt on the door adapted to swing over the plate to hold it in engaging position, and sealing means, holding the bolt in engagement with the plate.

55 Signed by me at Baltimore, Maryland.

THOMAS H. BAKER.
